UNITED STATES PATENT OFFICE

CHARLES C. VAN STRY, OF WEST ENGLEWOOD, NEW JERSEY, ASSIGNOR TO CAMERON MACHINE COMPANY, OF BROOKLYN, NEW YORK, A CORPORATION OF NEW YORK

SLITTING MEANS

Application filed April 5, 1930. Serial No. 441,755.

This invention relates generally to slitting devices, and has for its main object and feature the production of a score-cut slitting device that will act not only as a slitting means but also as a separating device.

In the accompanying drawings the invention is disclosed in several concrete and preferred forms in which:

Fig. 1 is a vertical sectional view of a slitting device embodying one form of the invention;

Fig. 2 is a detail sectional view substantially on the plane of line 2—2 of Fig. 1; and

Fig. 3 is a view similar to Fig. 1 showing a modified form of the invention.

1 indicates a backing member preferably having a "glass-hard" surface and 2 is a score-cut slitter to coat therewith to sever web of flexible material 3. When slitting webs of flexible material of a certain character by the score-cut process, it sometimes occurs that there remain a few unsevered threads between the slitted sections, and it has been the practice heretofore to employ a stationary blade that projects between the slitted sections to cut any remaining unsevered threads. It will be understood that such blades must need be adjusted very carefully to be in exact alinement with the line of slitting as otherwise adjacent slitted sections may become distorted out of the plane of severance to such an extent that said sections may overlap or be otherwise adversely affected. To avoid these difficulties, and to simplify construction, the expedient indicated in Fig. 1 is resorted to. As there shown, guiding means are provided to so lead the web of flexible material away from the slitting members as to cause said web to continue in engagement with the score-cut member after said web leaves the backing member, to thereby cause said score-cut member to act as a separating member as well as a slitting member. Or to state the proposition differently, the slitting and guiding means are so arranged with respect to each other that the score-cut and backing members first coat on the web and thereafter the score-cut member alone acts on the web while the

latter is traveling as an unsupported layer. In other words: the guiding means deflects the web of material, as it leaves the point of engagement of the score-cut and backing members, into a path inside the outer periphery of the score-cut slitting member. Obviously, said guiding means may take many forms. In Fig. 1 the guiding means are indicated at 4, said guiding means being in this instance the front winding drum of a surface-winding machine. It is to be understood, however, that the invention is not to be limited to use in a winding machine but may be utilized as an independent slitting means, or as a slitting means in other machines, such as printing machines, when no winding occurs.

In Fig. 3, backing member 5 is the front winding drum of a surface winding machine, and 6 indicates the score-cut slitting member 70 coating therewith. In this instance, web 7 is led over roller 8 and in between the slitting members. 9 indicates a guiding roller that deflects the web in the manner previously indicated and which then leads said web to the upper surface of the front winding drum. Preferably said roller 9 is mounted in two arms 10 that are adjustable about shaft 11 so that the extent to which slitter 6 penetrates between the slitted sections of the web is variable.

I claim:

1. Slitting means to sever a web of flexible material including: a backing member, a score-cut slitting member to coat therewith, and guiding means to so lead the web of flexible material away from the slitting member as to cause said web to continue in engagement with the score-cut member after said web leaves the backing member to thereby cause said score-cut member to act as a separating member as well as a slitting member.

2. Slitting means to sever a web of flexible material including: a backing member, a score-cut slitting member to coat therewith, and guiding means to deflect the web of flexible material, as it leaves the point of engagement of the score-cut and backing members, into a path inside the outer periphery of the score-cut slitting member.

3. Slitting means to sever a web of flexible material including: a backing member, a score-cut slitting member to coact therewith, guiding means to deflect the web of flexible material, as it leaves the point of engagement of the score-cut and backing members, into a path inside the outer periphery of the score-cut slitting member, and means to adjust the position of the guiding means to thereby 10 vary the extent to which the slitting member penetrates between the slitted sections of the web.

Signed at the city of New York, in the borough of Brooklyn, county of Kings and State 15 of New York, this 11 day of January, 1930.

CHARLES C. VAN STRY.
